PRESSING DEVICE

Harold A. Perkins, Cohoes, N. Y., assignor, by direct and mesne assignments, to New York Pressing Iron Company, Inc., New York, N. Y., a corporation of New York

Application July 6, 1936, Serial No. 89,044

7 Claims. (Cl. 38—41)

My invention relates to pressing machines and particularly but not exclusively to devices of this character adapted to press wearing apparel.

One of the objects of my invention is to provide a pressing device which will be extremely simple in its construction and operation and in which the pressure may be varied to any extent up to the structural strength of the machine itself. Another object is to provide a pressing device in which it will be impossible for the hands or any other portion of the body of the operator to be subjected to a pressure sufficient to cause pain or injury. More specifically, this last object includes the provision of coacting means whereby the development of an appreciable pressure between the pressing elements is positively prevented until they are moved substantially into contact or in such close proximity to each other that it is impossible for the fingers or hands of the operator to be between them.

In the fundamental embodiment of my invention, an object resides in the provision of a hydraulically operated press in which the pressing elements are entirely independent of the pressure developing mechanism except when said elements are substantially in contact, and in which the usual safety measure of providing control means requiring both of the operator's hands in a manipulation of the press is unnecessary.

In one embodiment of my invention, it is contemplated that an initial operation of the pressing device be performed by hand; however, in the preferred embodiment, it is proposed that an entire cycle of operation thereof be performed by supplied power. Hence, a further object of my invention resides in the provision of means for moving the presser head into close proximity to the buck and thereafter effecting a compression of the two pressing elements in response to an operation of power operated means. A further object resides in the provision of spaced means operable by hand for controlling the application of a comparatively high pressure to the presser head thereby forming a safety appliance for the benefit of the operator; and another object is to provide a further safety device whereby an operator is prevented from applying full pressure upon the presser head when the device is initially operated. A still further object resides in the novel arrangement and correlation of the various elements and control means of my pressing device in such a manner that the presser head will be initially actuated to a point predeterminedly spaced from the buck under a comparatively small moving force whereby it is impossible

for an operator accidentally to receive serious injury.

With these objects in view my invention includes the novel elements and combinations and arrangements thereof described below and illustrated in the accompanying drawings in which—

Fig. 1 is a side elevation of my device partially in section to show details of the construction and operation thereof;

Fig. 2 is a fragmentary vertical elevation, partially in section, showing the modification of a detail;

Fig. 3 is a fragmentary perspective view of the means for developing pressure and the controls for the machine;

Fig. 4 is an elevation view of the hydraulic cylinder partially in section;

Fig. 5 is an elevation view showing the details of a control valve;

Fig. 6 is a side elevation of a preferred embodiment of my device, partially in section and illustrating the various power transmitting elements in one position;

Fig. 7 is a fragmentary perspective view of a portion of the fluid circulating system and the control means associated therewith;

Fig. 8 is a diagrammatical representation of the fluid circulating system and devices included therein;

Fig. 9 is a view generally similar to Fig. 6 but showing the various power transmitting elements in another position;

Fig. 10 is a fragmentary front elevation view of the pressing device illustrating the hand operable controls;

Fig. 11 is a fragmentary side elevation view of Fig. 10; and

Fig. 12 is a fragmentary elevation view of the hydraulic piston with one of the regulating valves and an automatic control associated therewith.

Referring to Figs. 1 to 5, wherein I have illustrated one embodiment of my invention, my pressing machine comprises a cast frame 1 conforming in general to the frames now commonly employed and which is supported upon a base 2. 45 3 is the usual pressing bed or buck and 4 is the presser head which is carried by the arm 5 pivotally mounted on a shaft 6 secured in the frame 1, the arm 5 having a rearwardly extending arm or lever 7 carrying a counterweight 8. In my device this arm or lever 7 is provided with an opening 9 for a purpose which will be later described.

Referring first to Fig. 3, 10 is a motor which drives a liquid pump 11. The liquid to be pumped, preferably oil, is contained in the reservoir 12. 55

Centrally mounted on the base 2 of the frame is a cylinder 13 having its axis vertically disposed and having mounted therein a piston 14 adapted to be moved upwardly by hydraulic pressure developed by the pump 11. The cylinder 13 is mounted on a base 15 having a passage 16 therein communicating through the opening 17 with the cylinder below the piston 14. The pump 11 draws oil from the reservoir 12 upwardly through the pipe 18 and forces it through the pipe 19 into the passage 16 in the base of the cylinder 13. Communicating with the passage 16 is an outflow pipe 20 which conveys the oil back to the reservoir 12 through the operator-actuated valve 21 and the pipe 22. When the valve 21 is opened, it forms together with the pipes 20 and 22 an oil by-pass for the cylinder, and when no pressure is being exerted between the presser head and the buck the oil is constantly and freely circulated from the reservoir upwardly through pipe 18, through pipe 19, passage 16, pipe 20, valve 21 and pipe 22 back to the reservoir 12. When the valve 21 is closed, hydraulic pressure will be developed in the cylinder below the piston 14 and will force it upwardly. For the purpose of regulating the pressure which will be developed I provide the valve 23 which communicates with the pipe 19 as shown in Fig. 1 and also with the reservoir through the vertical pipe 24. A pressure gauge 30 is also installed in pipe 19 for the purpose of indicating the pressure in the liquid circulating system. By regulating the opening of the valve 23 by means of the hand wheel 26, the maximum pressure developed on the piston 14 may be controlled.

A piston rod 27 extends upwardly through the top head of cylinder 13 and carries the yoke 28 to which are pivotally connected the vertically depending links 29 and 30 at either side of the cylinder. These links, at the bottom, are pivotally connected to the lever 31 which is bifurcated as shown at 32 in Fig. 3 and pivotally mounted in the rear of the frame at 33 to form one element of a power-transmitting mechanism. The other element 34 of the power-transmitting mechanism extends in a substantially vertical direction and is pivotally connected to the lever 31 at 35 which point of connection is very close to the pivotal connection 33. The element 34 which leans a little to the left of the vertical as viewed in Fig. 1 forms a push-rod, the upper end of which is adapted to coact with the bottom of the lever 7 when the parts are in the relative positions shown in the dotted lines in Fig. 1, and thus transmits pressure from the hydraulic cylinder to the arm 5 thereby compressing the pressing elements 3 and 4. As the pressure in the cylinder 13 is relieved and the element 31 is returning from the position 31' to the position shown by the solid lines in Fig. 1, the upper end 55 of the rod 34 moves to the right (as viewed in Fig. 1) from the position 55' and enters the opening 9 in the lever 7 which is carried downwardly by the counterweight 8 to separate the pressing elements. The adjusting screw 57 is in this embodiment provided to insure this movement.

The valve 21 is actuated by the foot levers 36 and 37. These levers are pivotally mounted in the frame to move independently of each other as shown at 38. The valve 21 is closed by pushing the stem 39 (see Figs. 3 and 5) upwardly, and is opened by pulling the stem 39 downwardly. In order to accomplish these movements by means of the foot pedals 36 and 37 the valve 21 is pro-

vided with a depending yoke 40 in which an element 41 is pivotally mounted at 42. At the left, as viewed in Figs. 3 and 5, the element 41 is provided with an arm 43 which is pivotally connected to the stem 39 at 44; the arm 43 being provided with a slotted opening as shown at 45. Element 41 is also provided with slotted openings 46 and 47 in which are connected the operating levers for the valve 21. The rear end of the pedal lever 36 is connected with the element 41 at the left of the pivot 42 by means of a rod 48 and clevises 49 and 50 which are adjustable so that the effective length of the rod 48 may be varied. The rear end of the pedal lever 37 is also connected to the element 41 at the right of pivot 42 by means of the adjustable clevises 51 and 52 and the rod 53 as shown. From the foregoing, it will be apparent that when pedal 36 is depressed the stem 39 will be forced upwardly to close valve 21 and the rod 53 will be forced downwardly thus raising pedal 37 as pedal 36 is depressed. To open valve 21, pedal 37 is depressed which pulls stem 39 downwardly to effect this end.

In operation, assuming the valve 23 to be partially open, and the motor 10 to be running and oil to be circulating in the liquid circulating system, the garment to be pressed is placed upon the buck, and the presser head 4 is then lowered manually by grasping the handle 54. When the presser head 4 has been brought into contact with the buck or the garment thereon, the pedal 36 is depressed thus closing the by-pass around the cylinder. Oil pressure will be developed in the cylinder 13 and the piston 14 will be forced upwardly. This will raise the bifurcated end of the lever 31 which will permit the rod 34 to tilt backwardly until the top 55 moves to the position 55' beneath a solid portion of the lever 7. As the piston continues its upward movement, pressure will be applied to lever 7 through rod 34 and while there will be some slight upward movement of the push-rod 34, it will not move substantially from the position 34' shown in Fig. 1 while the pressure is applied. The maximum pressure developed will be indicated by gauge 25 and will depend on the extent to which valve 23 is closed. The desired pressure in the system may be regulated by means of the hand wheel 26, and it is unnecessary thereafter to change the valve setting unless a different pressure is desired. After pressure has been applied for a sufficient interval it is necessary only to depress lever 37 with the foot which will open the valve in the by-pass around the cylinder to relieve the pressure. As the lever 31 descends from the position 31' to the position 31, the rod 34, due to the coaction of the adjusting screw 57 with the lever 31, will tilt to the right until the upper end 55 reaches the opening 9 in lever 7, whereupon the counterweight will pull lever 7 downwardly and the pressing elements will separate. To repeat the operation it is only necessary to lower the head 4 into substantial contact with the buck, whereupon the upper end of the push-rod 55 will tilt back to the position 55', as pedal 36 is depressed, and the pressure to which the valve 23 has been adjusted will be developed between the buck and presser head. In order that the top 55 of rod 34 in tilting backwards may just clear the solid part of lever 7 with which it coacts when in the position 55', the length of rod 34 may be varied by the adjusting means 56.

If desired, the element 34 of the power-transmitting mechanism may be pulled forward from the position 34' into registration with the opening 75

9 simultaneously with the opening of valve 21 by means of the following mechanism. The lever 37 may be provided with an integral arm 58 to form a bell crank on the pivotal connection 5. The push-rod 34 may be connected to the upper end of this crank arm 58 by means of the rod 59, as shown in Fig. 2, and, in order to allow some downward movement of pedal 37 before a substantial pull is exerted on the rod 59 a helical 10 spring 60 may be provided intermediate the arm 34 and the nut 61 which connects rod 59 to the arm.

From the foregoing it will be apparent that in this embodiment of my device it is not necessary for the operator to have both hands occupied when pressure is applied between the buck and presser head in order to avoid the accidental crushing of the hands. This is so because the presser head must first be manually lowered 20 substantially into contact with the buck before the push-rod 34 of the power-transmitting mechanism will move to the left into pressing position as shown in the dotted lines in Fig. 1. Since the presser head and the buck are substantially 25 in contact before any hydraulic pressure can be applied it will be impossible for the operator to have any portion of his hands between the pressing elements when the pedal 36 is depressed.

In the preferred embodiment of my invention, I have designed a pressing device wherein the entire operation thereof is carried out by means of supplied power and which comprises associated elements preferably including a hydraulically operated piston, as will hereinafter appear, for moving the presser head into close proximity to the buck under a comparatively low pressure and thereafter effecting a compression of the two pressing elements under a comparatively high pressure. Referring to Figs. 6 through 12 which illustrate the preferred embodiment of my invention and particularly to Fig. 6, it will be noted that the frame of the press, the buck, presser head, hydraulic cylinder and associated power transmitting elements for actuating the presser head in response to the application of pressure to the piston of the cylinder, primarily, are substantially the same as the corresponding elements illustrated in Fig. 1. The lever 31 of the toggle which is connected to the links 29 and 30 associated with the piston of the cylinder 13, however, has connected thereto a link 61 at a point intermediate its length. Link 61 is pivotally connected to a cam 62 which in turn is pivotally mounted upon a shaft 63 secured in the frame of the machine. A member 64 which preferably comprises two coextensive, spaced parallel bars is pivotally supported on a shaft 65, secured to the frame of the press, the member 64 having pivotally secured at one end thereof a yoke 66 and at a point intermediate said yoke and shaft 65 a rotatably mounted cam follower 67 which is adapted to transmit motion from said cam to the member 64. A rod 68 which passes through 60 openings in the two arms of yoke 66 is maintained in position relative thereto by means of the collar 69 which is secured to the rod and a spring 70 interposed between the collar 69 and one arm of the yoke 66. The upper end of rod 70 68 is threaded as indicated at 71 whereby the same may be received in a threaded opening in a shaft 72 and adjustably secured thereto. Shaft 72 is rotatably mounted in a member 73 and extends through an opening 731 therein of a size 75 sufficient to permit rod 68 to extend there-

through and rotate to a limited degree about shaft 72. The member 73 is pivotally supported on the shaft 6 which supports arm 5 and the end thereof is formed operatively to engage the rearwardly extending arm or lever 7. An actuation 5 of the piston of the cylinder 13 to raise lever 31 of the toggle will, through link 31, rotate cam 62 which in turn will cause member 64 to pivot on shaft 65 and, through rod 68 and yoke 66, rotate member 73 and arm 5 about their pivotal axes. 10

The foregoing described combination of elements is utilized in moving the presser head 4 into close proximity with the buck 3 and accomplishes the same operation which in the first embodiment of my invention herein described 15 was accomplished by hand.

For a very efficient and practical method of power operation of my press and one particularly adapted for power control whereby the magnitude of the pressure applied to the pressing 20 elements is predeterminedly varied throughout the cycle of operation of the press, I have designed a fluid circulating system together with controls therefor which will best be understood by reference to Figs. 7 and 8. A pump 11 draws 25 fluid from the reservoir 12 and passes the same through the pipe 19 and into the base of the cylinder 13 as hereinbefore described with reference to Fig. 3. The base of the cylinder 13, 30 in this embodiment, is also connected through a pipe 74, in which a valve 75 is disposed, and through two pipes 76 and 77, in which valves 78 and 79, respectively, are disposed, and through pipe 80 back to the reservoir 12. The pipes 76 and 77 form parallel paths for the flow of fluid 35 so that fluid will still pass from cylinder 13 back to the reservoir 12 in the event one or the other of valves 78 and 79 are closed. The casing of valve 79, as illustrated in Fig. 7, is provided with a depending yoke 81 which forms a pivotal support for lever 82 to which is connected the shaft 83 for actuating the valve rod of the valve 79. Lever 82 has secured thereto as by means of a clevis 84 a rod 85 which in turn is secured to a foot-operated pedal 86 which is pivotally 40 supported on a shaft 87 extending transversely of the press and supported in the frame thereof. The lever 82 has also connected thereto a spring 88 which is connected to a lug 89, preferably secured to the base 2 of the frame, the spring 50 88 serving normally to maintain the valve 79 in open position.

The valve 78 which is disposed in the pipe 76 is provided with an operating lever 90 to which is adjustably secured a shaft 91 which is provided with an angularly disposed end portion adapted to be received in a slot 92 in the member 64 (see Fig. 6).

Valve 78 normally is in closed position when the elements of the pressing device are in the 60 position illustrated in Fig. 6 which, of course, is in the unactuated position of the presser head 4. Hence, when pedal 86 is depressed, thereby closing valve 79, valves 78 and 79 will be closed at the same time whereby the piston within the 65 cylinder 13 is subjected to the full fluid pressure which is developed by the pump 11 and limited by the valve 23 in the by-pass pipe 24. Under these circumstances, lever 31 of the power-transmitting mechanism will be raised and presser 70 head 4 will be moved toward the buck 3 by means of the cam and follower arrangement, hereinbefore described. It will be noted, however, that as member 64 is pivoted upwardly in response to the actuation of cam 62 the end thereof on the 75

opposite side of its pivotal axis will move downwardly to actuate lever 90 of valve 78 in a valve-opening direction. It will be seen, therefore, that upon an actuation of presser head 4 into pressing position, the fluid pressure exercised in carrying out this movement is limited and predeterminedly controlled by the manner in which the valves 78 and 79 are associated in the return line of the fluid circulating system and the correlated operation of the valve 78 with movement of the presser head.

The shaft 91 is adjustably secured to the operating lever 90 of the valve 78 by means of the adjusting nuts 93 which are threaded on the end 15 of the shaft and serve to regulate the degree of movement imparted to the lever through an operation of the member 64. Hence, it is evident that by adjusting the relative movements of the member 64 and lever 90 the presser head 20 may be moved toward the buck 3 under a desired pressure. Furthermore, in connection with the foregoing described operation of my press, it will be noted from an inspection of Fig. 9 that the cam 62 and follower 67 may be so designed 25 and arranged, although such a construction is not essential, that after a predetermined movement of the presser head 4 through an actuation of said cam and follower to position the same in close proximity to the buck 3 the cam follower 67 bears against the cam 62 at the point 30 94 which point represents the high point or point of maximum radial displacement of the periphery of the cam from its pivotal point toward the fulcrum of member 64. In other words, the cam 35 and follower may be designed to impart only a predetermined degree of movement to the presser head 4. Hence, in view of the configuration of the cam surface and because of the limited pressure under which the presser head is moved, 40 being substantially sufficient only to overcome the weight of the presser head and lever arm, it is possible for an operator to raise the presser head against the pressure transmitted thereto through the cam and associated mechanisms.

45 After the initial operation of my pressing device under supplied hydraulic power, as above described, it follows that the pressing elements are in position to be compressed under a comparatively high pressure head. To accomplish this result, I have interposed in the pipe 74 the valve 75 as illustrated in Figs. 7 and 8. The downwardly extending operating shaft 95 of the valve member of valve 75 is connected to a lever 96 which in turn is secured to a shaft 97 suitably 50 journaled in bearings in the frame 1 of the press. Shaft 97 also has secured thereto a lever 98 provided with a slot 99 within which is adapted to be received a depending link portion 100 of a yoke 101. The yoke 101 preferably extends to an 55 appreciable and preferably equal distance on both sides of the portion 100 and has pivotally secured at the ends thereof connecting rods 102 which extend upwardly and are connected at their upper ends to one arm 103 of bell cranks 60 104 (see Figs. 10 and 11). The bell cranks 104 are spaced an appreciable distance from each other and carry levers 105 which are disposed in a position to be actuated by the hands of the operator of the press. A spring 106 is preferably 65 provided and interposed between the frame of the press and arms 107 of the bell cranks in order to provide a cushioning effect when the bell cranks are operated. The two levers 105, connecting rods 102 and yoke 101 are associated 70 and designed to prevent the operator from rotat-

ing shaft 97 and thereby closing the valve 75 merely by depressing one of the levers 105. For example, if one of the levers 105 were depressed, yoke 101 would pivot about its point of connection with the connecting rod of the other lever and hence lever 98 and shaft 97 would be rotated to a considerably less extent than if both levers 105 were depressed together in which event full upward movement of the connecting rods would be imparted to the yoke 101. Obviously, valve 10 75 is arranged so that the movement of its operating shaft sufficient to close the same is of the order of a movement impartable thereto by said yoke only when both levers 105 are depressed together. In other words, the foregoing described combination of elements forms a safety device provided to insure against accidental injury to the hands of the operator.

Obviously, when the valve 75 is closed, the valves 78 and 79 are rendered, in effect, inoperative and the piston in the cylinder 13 will be subjected to the full, regulated pressure developed by the pump 11. In this connection, it will be understood that the element 34 of the power-transmitting mechanism will be operated in the same manner as hereinbefore disclosed relative to the embodiment of my invention illustrated in Figs. 1 to 5. That is to say, presser head 4 must be moved to a predetermined position relative to the buck 3 before it is possible for element 34 30 to be moved into operative engagement with the lever 7. When this has occurred, the operation of the press is effected in precisely the same manner as hereinbefore described.

In reference to a detail, it will be noted that 35 in the latter embodiment of my invention element 34 is provided with a bracket 108 and a shaft 109 is passed through an opening therein and secured to the lever 31 of the toggle. A compression spring 110 is interposed between the bracket and lever 31 and a compression spring 111 is interposed between the other side of the bracket and an adjusting nut 112. This arrangement forms a positive and resilient means for maintaining the element 34 in a cooperable position relative to the lever 7 and serves the same purpose as the combined adjusting screw and weighted construction disclosed in Fig. 1. In other words, spring 110 serves precisely to position element 34 in a position, when the presser 40 head and buck are closely spaced, to be moved initially upon an actuation of lever 31 into engagement with lever 7; and, after a pressing operation has been performed and the pressure relieved, spring 111 serves to return element 34 45 to its normal position wherein it passes within the opening 9 and permits the presser head 4 to return to its unactuated position.

In order to relieve the pressure in the cylinder 13 after a pressing operation has been effected, I 50 have provided a pedal 113, pivotally mounted on the shaft 87 and provided with a vertically extending arm 114 adapted to engage a lever 115 secured to the shaft 97. The arm 114 is preferably provided with an adjusting screw 116 in 55 order to permit relative adjustment between the arm 114 and lever 115. It will be noted that valve 78 is provided with the spring 88 for opening the valve when the pressure is relieved on the pedal 60 86; however, the valve 75 is adapted to remain in closed position after an operation of the hand levers 105 and, of course, will remain closed until pedal 113 is depressed and the shaft 97 is rotated in a direction to open the same.

By way of a further safety appliance, I have 75

provided means, illustrated in Fig. 12, which is designed to prevent an operation of the press through a complete cycle in response to a depression of the two, hand-operated levers 105. The base of the cylinder 13 is here illustrated as including a passage 117 which is adapted to communicate with the cylinder and valve 75. It will be seen that the exteriorly extending pipe 74 is dispensed with in this design of my invention and that a more compact assemblage is effected. It will be noted in this connection that the operating shaft 95 of valve 75 extends vertically thereabove and has connected thereto, by suitable means including, for example, a pin and slot construction, the lever 96 which in turn is secured to the shaft 97. A collar 118 is adjustably secured on the shaft 95 and a helical spring 119 surrounds the shaft and is interposed between the collar 118 and a movable washer 120 which is adapted to bear against a lever 121. Lever 121 is pivotally mounted upon a shaft 122 secured in suitable bearings 123 provided on a beam 124 extending transversely of the frame 1. The end of lever 121, as indicated at 125, is designed to extend beneath the yoke 28 connected between the piston shaft 27 and the links 29 and 30 of the piston assembly. Inasmuch as shaft 95 of the valve 75 extends through a suitable opening in the lever 121, the collar 118 and compression spring 119 will permit only a limited movement of the shaft 95, depending upon the adjustment of the collar but insufficient to vary the fluid pressure in the cylinder, in response to an operation of the hand levers 105 and thereafter the pressure applied to said levers will be transmitted to the lever 121 and, obviously, movement of this lever is prevented through its engagement with the yoke 28. However, the above elements are so designed and arranged that when yoke 28 has been raised to its maximum height under the joint control of the valves 78 and 79, it will then permit sufficient movement of shaft 95 to close valve 75 to effect a pressing operation. Hence, with this arrangement, the operator is prevented from effecting a pressing operation of my pressing device merely by depressing the hand-operated levers. The spring 119 may be dispensed with and the collar 118 secured to shaft 95 in close proximity to the lever 121. However, the spring tends to reduce noise and effect a smoother operation.

In view of the hereinbefore described operation of the various elements of my press in conjunction with the specific descriptions thereof, the cycle of operation of the press in its entirety should be clear from the following description of the method of operation thereof. Assuming that a garment or like object is arranged on the buck, the operator depresses pedal 86 and maintains the same depressed against the operation of spring 88 while the presser head 4 is moved under a comparatively low pressure head into close proximity to the buck 3. Thereafter, by depressing the hand levers 105, a compression of the two pressing elements is effected under a comparatively high, predetermined pressure head and, upon a depression of pedal 113 the pressure is relieved and presser head 4 moves upwardly under the gravitational effect of the weight 8 to its original, unactuated position, the various elements being then positioned in readiness for a second operation.

Although I have illustrated and described a particular fluid circulating system as a power means, it will be understood that equivalent ar-

rangements thereof and of the elements associated therewith may be made and, although I refer to oil as a medium of pressure transmission, other suitable fluids may also be used.

While I have described my invention in its preferred embodiment, it is to be understood that the words which I have used are words of description rather than of limitation. Hence, changes within the purview of the appended claims may be made without departing from the true scope and spirit of my invention in its broader aspects.

What I claim is:

1. In a pressing device of the character described comprising a movable presser head and a buck, hydraulic-pressure actuated means including a cylinder and piston for moving said presser head toward said buck, manually operable means for effecting an operation of said hydraulic means to move said presser head toward said buck, means for controlling the pressure in said cylinder, means for operatively connecting said presser head with said control means; said connecting means being so constructed and arranged that movement of said presser head toward said buck effects an operation of said control means progressively to reduce the pressure in said cylinder whereby said presser head is moved into closely spaced relation to said buck under a comparatively low pressure, and means for effecting, when said presser head and buck are so closely spaced, an operation of said hydraulic means to urge said presser head toward said buck under a comparatively high pressure.

2. In a pressing device of the character described comprising a movable presser head and a buck, a fluid circulating system including a fluid circulating pump, a fluid supply reservoir, a cylinder and conduits communicating with said reservoir and cylinder for supplying fluid to said cylinder and returning it to said reservoir, said cylinder being provided with a piston operatively connected to said presser head, a first valve disposed in said system and manually operable to control the fluid pressure in said cylinder and a second valve disposed in said system including valve-operating means operatively connected with said presser head, said valves being so constructed and arranged in said system that said first valve may be manually actuated to effect an operation of the piston in said cylinder to move said presser head toward said buck under the fluid pressure developed in said system and said second valve being operable progressively to decrease the pressure in said cylinder as said presser head approaches said buck.

3. In a pressing device of the character described comprising a movable presser head and a buck, a fluid circulating system including a fluid circulating pump and a cylinder provided with a piston, means for transmitting motion from said piston to said presser head, said system including a fluid supply reservoir, means for supplying fluid to said cylinder and means for returning it to said reservoir including two parallel paths for the flow of fluid therethrough, a first, normally closed valve disposed in one of said parallel paths including a valve-operating mechanism and means for connecting said mechanism with said presser head, and a second valve disposed in the other of said parallel paths and manually operable to closed position whereby to effect an operation of said piston to move said presser head toward said buck, said first valve being operable progressively to decrease the pressure in said

cylinder as said presser head approaches said buck.

4. In a pressing device of the character described comprising a movable presser head and a buck, a fluid circulating system including a fluid reservoir, a fluid circulating pump and a cylinder provided with a piston operatively connected with said presser head for developing pressure between said head and buck, a conduit for supplying liquid from said reservoir to said cylinder and returning it therefrom to said reservoir, means connected in said conduit and manually operable to effect an operation of said piston to move said presser head toward said buck, means for progressively decreasing the liquid pressure exerted on said piston as it is actuated to move said presser head toward said buck, means for thereafter effecting an operation of said piston to urge said presser head toward said buck under a comparatively high pressure, means forming a by-pass for liquid around said cylinder and an adjustable valve disposed in said by-pass for regulating the liquid pressure developed in said system.

5. In a pressing device of the character described comprising a movable presser head and a buck, the combination with fluid-operated means comprising a cylinder provided with a piston, of manually operable means for effecting a fluid-actuated operation of said piston, means for transmitting motion from said piston to said presser head for a fraction only of the full stroke of said piston, means for controlling the pressure of said fluid and means actuated by said fluid-operated means during the movement thereby of said presser head toward said buck for operating said control means progressively to reduce said fluid pressure as said presser head approaches said buck whereby said presser head may be

moved to a position closely spaced from said buck and held there under comparatively low pressure.

6. In a pressing device of the character described comprising a movable presser head and a buck, the combination with hydraulic means comprising a cylinder provided with a piston of manually operable means for effecting an actuation of said piston, a first means for transmitting motion from said piston to said presser head for a fraction only of the full stroke of said piston, means for progressively decreasing the pressure exerted by said piston during said actuation thereof whereby said presser head may be moved to a position closely spaced from said buck and held there under comparatively low pressure, a second means for transmitting motion from said piston to said presser head, said second means including means movable operatively to connect said piston with said presser head only when said head lies in closely spaced relation to said buck and means for thereafter effecting an operation of said piston under a comparatively high pressure.

7. In a pressing device of the character described comprising a pair of relatively movable presser elements, a fluid circulating system, fluid-operated means in said system for moving one of said elements toward the other under pressure, a valve in said system and an operating handle therefor and means for operatively connecting said handle to the element moved by said fluid-operated means; said connecting means being so constructed and arranged that said valve is automatically operated progressively to decrease the pressure under which said one element is moved as it approaches the other element.

HAROLD A. PERKINS.
